96,278

DESIGN FOR A TEXTILE FABRIC

Walter Robinson and Joseph Westemeyer,
New York, N. Y.

Application June 5, 1935, Serial No. 57,134

Term of patent 3½ years

To all whom it may concern:

Be it known that we, Walter Robinson and Joseph Westemeyer, citizens of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a plan view of a piece of textile fabric showing our new design.

The dominant feature of our design resides in

the contrasting appearance of the dull impressed matt surfaced elements on a lustrous or shiny pile fabric, as indicated on the drawing.

The dot and dash lines on the drawing, outlining the design unit, which unit is repeated in regular succession as indicated.

We claim:

The ornamental design for a textile fabric, substantially as shown and described.

WALTER ROBINSON.
JOSEPH WESTEMEYER.
